UNITED STATES PATENT OFFICE.

REINHOLD KRUMMING, OF MILWAUKEE, WISCONSIN.

BOOK HOLDER OR SUPPORT.

1,079,418.

Specification of Letters Patent.

Patented Nov. 25, 1913.

Application filed January 6, 1913. Serial No. 740,451.

To all whom it may concern:

Be it known that I, REINHOLD KRUMMING, a citizen of the United States, residing at Milwaukee, Wisconsin, have invented 5 certain new and useful Improvements in Book Holders or Supports, of which the following is a specification.

This invention relates to improvements in book holders or supports.

10 In the use of books such as temporary post binders now considerably used for catalogue purposes, there is a tendency for the book to close when opened and laid upon its back, thereby causing inconvenience and annoyance to users of such books.

The main objects of this invention are: First, to provide in a temporary binder or loose sheet book, an improved support or holder for supporting the book in its open 20 position or with its covers extended. Second, to provide an improved book holder or support for temporary binders of the telescoping book type, which does not materially change the construction of such binders. Third, to provide an improved book 25 holder or support permanently attached to the book, adapted to be collapsed, which, when collapsed, is entirely out of the way, and one which does not materially change 30 or detract from the appearance of the book. Fourth, to provide an improved book holder or support which may be quickly and easily adjusted to operative position or collapsed to inoperative position.

35 Further objects, and objects relating to structural details, will definitely appear from the detailed description to follow.

I accomplish the objects of my invention by the devices and means described in the 40 following specification.

The invention is clearly defined and pointed out in the claims.

A structure which is a preferred embodiment of my invention is clearly illustrated 45 in the accompanying drawing forming a part of this specification, in which:

Figure I is a perspective view of a temporary binder of the extensible post type embodying the features of my invention, the 50 back holder or support being collapsed, the binder being shown with the covers extended. Fig. II is an enlarged perspective of the structure appearing in Fig. I, with the supports extended. Fig. III is a detail perspective view of the structure shown in 55 Figs. I and II disposed upon its back, the

covers being shown in an upright position. Fig. IV is an enlarged detail section on a line corresponding to line 4—4 of Fig. II.

In the drawing, similar reference numerals refer to similar parts throughout the several views.

Referring to the drawing, the covers 1 are provided with cover members 2 and 3. The cover members 2 and 3 are provided 65 with overlapping flange-like back members 4 and 5 respectively, as is quite common practice in binders of this type. The binding member 2 is provided with tubular binding post members 6 and 7, while the member 3 is provided with post members 8 and 9 adapted to telescope in the members 6 and 7. The post members are adjustably secured by means of the screws 10. The central post member 9 is not an adjusting member, but 75 is provided with a spring 11 tending to force the cover members apart. As the details of the binding posts form no part of my present invention, they are not further illustrated or described herein. The back 80 members 4 and 5 are supported in a spaced relation to provide a slot-like opening in the back of the book by the binding post members which are associated to telescope as above described. The bar-like supporting member 12 is pivotally mounted on the inner back member 4 to swing or collapse between the back members,—see Fig. I—the pivot 13 being arranged centrally of the supporting member so that it may be swung 85 transversely of the back, as shown in Figs. I, III and IV. Being mounted upon one of the back members, it does not interfere in any way with the adjustment of the binder, and when the support is collapsed, the 90 binder may be manipulated and handled as though the support were not present.

The cover member 3 is provided with a longitudinal slot 14 through which the support swings when extended, the end of the 100 slot serving as a stop to limit the swing of the support. The support is of such length that one end projects slightly at the lower end of the back when it is collapsed, so that it may be swung to its extended position by 105 placing the finger on the end thereof. When collapsed, the support does not materially change the appearance of the binder and does not in any way interfere with its manipulation. When the support is in the extended position, the back is held upright so 110 that the tendency to close is prevented.

I have illustrated and described my improvements as embodied in a temporary binder of the extensible post type. It may be readily adapted for other types of binders or even permanently bound books provided with suitable recesses or openings in their backs adapted to receive the supporting member.

I have not attempted to illustrate or describe the various modifications which I contemplate as such modifications will, I believe, be readily understood by those skilled in the art to which this invention relates. I desire, however, to be understood as claiming my improvements specifically in the form illustrated as well as broadly within the scope of the appended claims.

Having thus described my invention, what I claim as new and desire to secure by Letters Patent is:

1. In a temporary binder, the combination with the cover members provided with overlapping back members, means for adjustably connecting said cover members, said back members being supported in a spaced relation, and a supporting bar pivotally mounted on the inner back member to swing between the back members, the cover member having the outer back member thereon being longitudinally slotted to permit the bar being swung through the slot to a position transverse of the back members and being collapsed between the back members.

2. In a temporary binder, the combination with the cover members provided with overlapping back members, means for adjustably connecting said cover members, said back members being supported in a spaced relation, and a supporting bar pivotally mounted on the inner back member to swing between the back members or to a position transverse of the back members.

3. In a temporary binder, the combination with the cover members provided with overlapping back members, adjusting means for said binder whereby said cover members are adjustably connected, and a supporting bar disposed between the back members and

pivotaly mounted to one of them to swing 50 between them, the cover member having the outer back member thereon being longitudinally slotted to permit the supporting bar being swung through the slot to a position transverse of the back members. 55

4. In a temporary binder, the combination with the cover members provided with overlapping back members, means whereby said back members are adjustably connected, and a support mounted on one of said back members to collapse between the same. 60

5. In a temporary binder, the combination with the cover members provided with overlapping back members, means whereby said back members are adjustably connected, and a support mounted to collapse between the back members or to be extended transversely thereof. 65

6. A book support comprising in combination, the cover members provided with 70 back members supported in a spaced relation, and a support member pivotally mounted between the back members to swing between them or to a position transverse thereof. 75

7. A back support comprising in combination, a back having a longitudinal slot-like opening therein, and a supporting member pivotally mounted in said opening to collapse into the opening or to be swung 80 transversely of the back, the supporting member being inclosed by the back when in its collapsed position.

8. A back support comprising in combination, a back having an opening therein, 85 and a supporting member mounted in said opening to collapse therein or to be extended transversely of the back, the supporting member being inclosed by the back when in its collapsed position. 90

In witness whereof, I have hereunto set my hand and seal in the presence of two witnesses.

REINHOLD KRUMMING. [L. S.]
